UNITED STATES PATENT OFFICE

JAMES P. ERIKSEN, OF NEW YORK, N. Y., ASSIGNOR TO AMERICAN BANK NOTE COMPANY, OF NEW YORK, N. Y., A CORPORATION OF NEW YORK

SHEET-DELIVERY MACHINE

Application filed March 28, 1929. Serial No. 350,500.

My invention relates to sheet delivery machines, and more particularly to the construction of the delivery or collecting shelf of such machines.

5 In certain rotary steel plate or undersurface printing machines, the printed sheets as they pass from the delivery tapes are received by, and wound in, a web of paraffine or other paper so treated as to avoid offsetting of ink 10 and drying of wet sheets, in which they are stored until the next operation is required upon the sheets. At such time the roll of paraffined or otherwise treated paper is passed through what is known as an unwinding 15 machine by which the sheets are removed from the roll and conveyed by delivery tapes to a delivery or collecting shelf where they are accumulated in a pile.

My present invention, while shown as being used in connection with a particular type of unwinding machine, is directed solely to the delivery or collecting shelf mechanism, and has for its object the provision of a shelf which may be set at any desired angle to the 20 delivery tapes, and brought to any desired elevation without disturbing this angle, the means for raising and lowering the shelf having associated therewith a mechanism actuated as a result of the movement of said shelf 25 to automatically maintain a predetermined spacing of the tail or back board and the discharge point of the delivery tapes. This mechanism is also operative to maintain the relative positions of the tail or back board of 30 the shelf and the discharge end of the delivery tapes, during any change of angularity of the delivery or collecting shelf, and irrespective of any change in elevation of the shelf.

35 In addition to the characteristics above referred to, the top plate of the shelf, which serves as a support for the wetting board, may be adjusted laterally of the unwinding machine to accurately position the side gauge board in relation to the line of travel in the sheet, so that the side gauge board, in conjunction with the tail or back board, may serve to accurately position succeeding sheets in a pile and avoid the necessity for the use 40 of joggers or other appliances.

In the delivery or collecting shelf of my invention, the same mechanisms used for setting the shelf at a desired angularity to the delivery tapes may also be used for bringing the shelf to a horizontal position to facilitate 55 the removal from the shelf of the wetting board and the pile of sheets thereon.

The mechanism actuated as a result of the vertical movements of the shelf includes 60 therein a lever connected with said shelf, the pivotal movements of which result in the movement of the shelf and its appurtenances toward or from the delivery tapes, according to whether the shelf is being lowered or raised. The construction of this lever, and 65 the manner of connecting it with the shelf are such as to compensate for the increased leverage of the lever during its actuation as a result of the vertical movement of the shelf and its actuating means, while permitting a 70 change in the angularity of the shelf, unaccompanied by or during such movement, if desired.

Aside from the manual control of the power for raising or lowering the shelf, the 75 adjustments of the shelf resulting in the maintenance of the desired relation between same and the delivery tapes is entirely automatic.

The invention consists primarily in a sheet 80 delivery machine including therein a collecting mechanism embodying a cylinder, a plunger mounted therein, means controlling the application of power to said plunger, a frame carried by said plunger, a collecting 85 shelf slidably mounted upon said frame, a lever pivotally connected and movable with said plunger and set obliquely of the axis thereof, a bearing member engageable with said lever, and operative connections between 90 said lever and said shelf, whereby the oscillations of said lever with the vertical movements of said plunger will impart movement to said shelf along said frame; and in such other novel features of construction and combination of parts as are hereinafter set forth and described, and more particularly pointed out in the claims hereto appended.

Referring to the drawings,
Fig. 1 is a side view of an unwinding ma-

chine embodying therein a collecting shelf embodying my invention;

Fig. 2 is an enlarged side view of the collecting shelf mechanism, partly broken away;

Fig. 3 is a rear view of one side of the collecting shelf and its actuating mechanism;

Fig. 4 is a plan view of a portion of the frame above the hydraulic lift;

Fig. 5 is a plan view of the table proper;

Fig. 6 is a bottom plan view of the table proper and its supporting frame; and

Fig. 7 is a side view of the table proper and its supporting base.

Like numerals refer to like parts throughout the several views.

In the embodiment of the invention shown in the drawings, I have indicated at 10 an unwinding machine, including therein delivery tapes 11. These form no part of my invention which relates more particularly to the delivery or collecting mechanism shown to the right of the delivery tapes in Fig. 1.

This mechanism consists of a cylinder 12, having a vertical axis. Slidably mounted therein is a vertically movable plunger 13 carrying a suitable piston shown in dotted lines in Fig. 3.

A cross plate 14 is connected with said plunger by means of lugs 15, rotatably mounted upon a bearing pin 16 fixedly supported in lugs 17 upon the head of said plunger 13. Said bearing pin also has secured thereto the segment of a worm wheel 18, being thus also fixed in its relation to the plunger.

Mounted in suitable bearings 19 upon the plate 14 is a worm shaft 20, enmeshed with the worm segment 18, and having an operating handle 21 in a position convenient to the operator of the machine who sits adjacent the delivery or collecting shelf. This manner of mounting the plate 14 permits the base frame to be set at any desired angle to the horizontal, or to be brought to a horizontal plane by merely turning the worm shaft 20 in one direction or the other.

I also provide the head of the plunger 13, toward the delivery tapes 11, with a stop 22 limiting the pivotal movement of the plate 14 so that when turned toward said stop, it cannot pass beyond a horizontal plane, see Fig. 2.

The plate 14 carries a base frame having parallel side bars 23 and 24, and a single end bar 25, in which the worm shaft 20 is mounted, as shown more particularly in Fig. 6. It will thus be noted that with the actuation of the worm shaft 20, it will have movement circumferentially about the worm wheel segment 18, thus imparting turning movement to the plate 14 and to the bars 23, 24 and 25 of the base frame, and that with the vertical movement of the plunger 13, the setting of said frame will remain unchanged.

The side bars 23 and 24, upon the upper surface thereof, carry bearing straps, those

upon the bar 23 being indicated at 26 and 27, and those upon the bar 24, at 28 and 29. Slidably mounted upon the plunger frame by means of said bearing straps is the collecting shelf which includes a carriage 30 and a collecting shelf proper 31, the former of which for convenience may be termed a "floating" carriage, since, while it will have movement with a change of angularity of the base frame about the pin 16, this movement will also always be accompanied by a sliding movement of the carriage in relation to said base frame. Said carriage will thus have a floating movement during said turning movement, and also with a vertical movement of the plunger 13, as will more fully appear hereinafter.

The collecting shelf proper 31 is mounted upon the carriage 30 by means of bearing straps 32 and 33 in which one end bar of said carriage 30 is slidably mounted, and bearing straps 34 and 35, in which the other end bar of said carriage is slidably mounted. This manner of mounting the collecting shelf or table proper 31 upon the carriage 30 permits the adjustment of said shelf or table laterally of said carriage while causing movement of the carriage toward and from the tapes 11 to impart similar movement to the shelf or table proper.

By the construction heretofore described, the collecting shelf or table 31 may be positioned with any degree of angularity to a horizontal plane through the adjustment of the base frame and by means of the worm wheel segment 18 and the worm shaft 20; the carriage 30 may have movement with the shelf or table 31 toward or from the delivery tapes 11, and the shelf or table 31 may be adjusted laterally of the carriage 30.

The setting for angularity and the adjustment of the table are manual operations. The longitudinal movement of the carriage 30 and the shelf 31 are entirely automatic resulting in one instance from the actuation of the worm shaft 20, and in another instance as a result of the actuation of mechanisms made operative during the rise or fall of the plunger 13.

The mechanism for laterally adjusting the collecting shelf or table 31 will first be described. Extending between the end bars of the carriage 30 is a bar 36 in which is mounted a shaft 37 having a hand wheel 38 at one end thereof, and a bevelled gear 39 at the other end thereof. Rotatably mounted in the end bars of the carriage 30 is a shaft 40 carrying a bevelled gear 41 enmeshed with the bevelled gear 39. This shaft is supported adjacent said gears by a bracket 42 carried by the cross bar 36.

Carried by this shaft 40, adjacent the end bars of the carriage 30, are spur gears 43 and 44 meshing respectively with racks 45 and 46 carried by the shelf or table 31 upon the under

face thereof. It will be noted that with the turning of the shaft 40 the shelf or table 31 will be moved laterally of the carriage 30, according to the direction of movement of the shaft, but that beyond this lateral movement there is no disturbance of the relation between the carriage 30 and the shelf or table 31, and that this adjustment is entirely independent of any angular movement of the carriage and shelf or table about the bearing pin 16, and is affected in no wise thereby. It is also obvious that any movement of the carriage 30, longitudinally of the side bars 23 and 24, will have no effect whatever upon the lateral adjustment of the shelf or table 31 by means of the shaft 40 and the mechanisms co-operating therewith.

The table or shelf proper 31, upon the upper face thereof, is provided with a longitudinally extending undercut slot 47, by means of which a tail or back board 48 is mounted thereon, its position being perpendicular to the plane of said shelf or table. The slot above referred to permits adjustment of said tail or back board longitudinally of said shelf or table. As will be noted, however, by Figs. 1 and 2, when the table or shelf is in position for receiving sheets from the tapes 11, different portions of the height of the tail or back board will be at different distances from the delivery point of the sheets by said tapes.

The main purpose of the invention is to automatically advance the shelf or table toward the tapes from time to time during the operation of the unwinding machine; so that at all times the portion of the tail or back board 48 operative to receive sheets will be positioned substantially the same distance from the delivery point of said tapes when the height of the pile of collected sheets is great enough to require the lowering of the shelf or table 31 to permit the continued delivery of sheets thereto.

Removably mounted upon the shelf or table 31 is a side gauge board 49, the shelf or table being provided with two series of openings 50 and 51 adapted to receive tongues upon said side gauge board 49. A number of such openings is provided to permit the setting of this board 49 as required according to the width of sheet being delivered at any one time. The lateral adjustment of the shelf or table by means of the shaft 40 is to compensate for any inaccuracy in the setting of the side gauge board 49.

This side gauge board is made removable in order to permit convenient access to the wetting board and the pile of sheets thereon when it is required to remove same from the shelf or table 31.

While I have referred to the automatic readjustment of the position of the tail or back board 48, in order to maintain a substantially constant spacing thereof from the

delivery point of the tapes 11, it will be understood that this adjustment is a mere approximation, since by the very nature of the mechanism it cannot be an accurate adjustment. For example, the vertical adjustment of the height of the collecting shelf or table is intermittent, since several hundred sheets may be accumulated thereupon before such adjustment is necessary. The distance of the tail or back board at the top of such a pile of several hundred sheets will necessarily be slightly farther away from the delivery point of the tapes than the bottom of said pile, but the difference will not be sufficiently great to prevent a neat stacking of the sheets. With the lowering of the shelf, however, the back board, in its entirety, will be advanced, irrespective of the quantity of the vertical movement, so that the top of the accumulated pile of sheets, at the time of such adjustment, will be advanced so that it will occupy substantially the same vertical plane at the point of contact with the tail or back board as was occupied when the first sheet of the pile was delivered to the shelf or table.

By means of the mechanism which I will now describe, the tail or back board 48 will be automatically advanced with each lowering of the shelf or table to an extent so that the portion of the tail or back board immediately above the collected pile of sheets will occupy substantially the same position with relation to the delivery point of the tapes 11, irrespective of the height of the pile of sheets upon the shelf or table.

The mechanism above referred to is duplicated upon opposite sides of the cylinder 12 and plunger 13, so that a description of but one of these mechanisms is necessary. One of such mechanisms is shown in detail in Figs. 2 and 3, dotted positions thereof being shown in Fig. 2.

Each such mechanism comprises a slide 52, mounted in a slideway 53 formed exteriorly of the cylinder 12. This slide carries an offset bracket 54 to which is pivotally connected a cam lever 55. This cam lever has slidably mounted thereon a link 56, secured thereto by means of elongated slots 57 in said link, and spaced bearing studs 58 carried by said cam lever.

The upper end of the link 56 is pivotally connected with a bracket 59 secured to the carriage 30. The pivotal connection between the lever 55 and bracket 54 is upon one side of the axis of the cylinder 12 and plunger 13, while the carriage bracket 59 is connected with the carriage 30 upon the other side of said axis, thus causing said lever to be normally set obliquely to the axis of said plunger and said cylinder.

Carried by the cylinder in substantially the plane of the axis thereof is a bearing member 60, this member preferably being in the form of an anti-friction roller adja-

cent the top of said cylinder so as to be in constantly engaging relation with the cam surface 61 of the lever 55.

The slide 52 is connected by a fixed link 53 with the bearing pin 16 upon the head of the plunger 13, so that the slide 52 and lever 55 will have vertical movement simultaneously with the vertical movement of said plunger. The link 56 also has vertical movement with the lever 55, but to a variable extent as determined by the movement of the carriage 30 as a result of the oscillations of said lever and link, due to the obliquity of its setting and its movement past, while in engaging relation with, the bearing member 60.

It will be noted that the cam surface 61 upon the lever 55 is arcuate. Since the carriage 30 and the bracket 59 can have only a right line movement, the link 56 will, during the oscillations of the lever 55 upon the descent of the plunger 13, have sliding movement in relation to the cam 55 with the movement of the carriage 30 towards the tapes 11. This action, however, will result in a variance in the effective leverage of the lever 55 and the link 56 which would, were it not for the curvature of the cam surface 61, result in a greater quantity of movement of the shelf 31 toward the tapes 11 at different elevations of the plunger, or during different stages of its vertical movement. Hence the curvature of this surface has the effect of equalizing the quantity of movement of the collecting shelf 31 or table with the same quantity of vertical movement of the plunger, irrespective of the elevation of the table. The bracket 54 also has movement away from the member 60, thus causing a constant decrease of the leverage effective to impart angular movement to the lever 55. The curved cam surface 61 also compensates for the varying leverage. The intermittent progressive movement of the shelf or table 31, toward the delivery point of the tapes 11 with a given movement of the plunger at any stage of its movement, secures a very close approximation of exactitude in the positioning of the back or tail board 48 with relation to the delivery tapes at every elevation at which the said shelf may be set.

By slidably mounting the link 56 in relation to the lever 55, angular adjustment of the cross plate 14 and the base frame carried thereby, and the parts supported from said base frame, is permitted, although there will be automatic adjustment of said base frame in relation to the carriage 30 and the shelf or table 31 during such angular adjustment, by reason of the radial distance of the bracket 59 from the axis about which the base frame has movement. This will more fully appear hereinafter.

The cylinder 12 is preferably actuated by means of hydraulic power since the absence

of elasticity in such power is desirable, in view of the constantly changing weight of the load upon the collecting shelf or table 31. Hydraulic power is illustrated in the accompanying drawings, the delivery water pipe being shown at 63, the valve controlling same at 64, while the exhaust water pipe is shown at 65 and the valve controlling same at 66.

For convenience of assembly, the bearing member 60 is shown as being carried by a plate 67 extending across the slideway 53, thus leaving clearance for the link 62.

The operation of the herein described mechanism is substantially as follows:—

Assuming that no sheets are stacked upon the shelf or table 31, and that the parts are in the position shown in Fig. 2, in full lines, sheets will be delivered one at a time upon the wetting board upon the shelf 31 until the height of the collected pile is such as to interfere with the flight of a sheet after leaving the tapes 11 and with the proper settling of the sheet upon the stack in engagement with the rear or tail board 48 and the side gauge board 49.

It will also be assumed that the height of the accumulated pile is one-tenth of the ultimate height of the complete stack of sheets, and that with the accumulation of sheets upon the shelf or table 31, it is necessary, from time to time, to lower said table or shelf, each lowering movement being approximately one-tenth of the height of the back or tail board 48. This, however, is not a fixed condition, but is merely assumed for purposes of explanation and the operation of the collecting shelf mechanism.

As shown in the drawings, Fig. 1, the back or tail board 48 is set in a plane oblique to the axis of the cylinder 12, but substantially perpendicular to the plane of flight of the tapes 11. Consequently, the portion of the back or tail board below this plane of flight will be at substantially the same distance from the delivery point of the tapes, and all portions of the board above this plane of flight will be more remote from this point of delivery. If the tail board, during the various stages of lowering same, had merely a vertical movement, this would result in a change in its spacing from the delivery tapes, because it would have merely a parallel movement.

The correction of this condition is one of the objects of the present invention, the construction of the actuating mechanism being such that during the vertical movement of the plunger 13, the back or tail board will receive a right line movement toward the delivery tapes, the simultaneous vertical and right line movements above referred to resulting in movement of the back or tail board in the plane oblique to the axis of the cylinder 12 in which it is set.

With the condition assumed, where the

downward movements of the collecting shelf or table 31 amount to one-tenth of the height of the back or tail board, each one-tenth portion of the height of the tail board may, by such downward movement, be brought to approximately the same position as that occupied by each preceding one-tenth portion.

The above conditions are accomplished by merely releasing the pressure within the cylinder 12, thus permitting the plunger 13 and the parts carried thereby to descend. With the descent of the plunger, the slide 52 moves therewith in the ways 53, and the cam lever 55 moves in relation to the bearing members 60, being thrust as a result of such movement toward the tapes 11. The movement of the cam lever 55 causes the link 56 to impart a thrust upon the carriage 30 and the table or shelf 31 carried thereby and movable therewith, toward the tapes 11, the movement of said carriage and said shelf being a right line upward movement.

While the lever 55 will have the same vertical movement as the plunger 13, the link 56 cannot have this same quantity of vertical movement because of the sliding of the carriage 30 upon the inclined base frame. It is for this reason that the link 56 is slidably connected with the cam lever 55.

It is obvious that this movement of the link 56 in relation to the lever 55 permits an increase in the distance between the brackets 54 and 59 and in the effective leverage of the lever 55 and link 56, notwithstanding the normal arc of movement of the link 56 when connected with the bracket 59.

With the initial downward movement of the link 56, it will, during its arc of movement toward the tapes 11, rise to an extent substantially the same as the ascent of the bracket 59. With a continued downward movement, however, its rise during its arc of movement will be proportionately less than the rise of the bracket 59, so that it must move outwardly along the lever 55, thus increasing the effective leverage of the lever 55 and said link. The variation in the effective leverage of the lever 55 and link 56 is modified by the arc described by the link 56 at its point of connection with the bracket 59. By curving the cam surface 61 as described, the angular movement of the lever 55 with a given quantity of movement of the plunger 13 may be decreased to an extent to compensate for the increased effective leverage of said lever and said link.

As the plunger 13 descends, however, the point of pivotal connection between the lever 55 and the bracket 54 will move away from the bearing member 60, thus progressively decreasing the angular movement of said lever with the continuing descent of the plunger. This decrease, however, during the early stages of the descent of the plunger, is disproportionate to the increase of the effec-

tive leverage at which the lever 55 and link 56 act upon the carriage 30. The curved cam surface 61, however, is so formed that in addition to compensating for the increased leverage at which the lever 55 and link 56 act, it will increase the angular movement of the lever 55 during the later stages of descent of the plunger to compensate for the effective leverage at which the bearing member 60 acts in relation to said lever. In practice, 75 the curved cam surface 61 will have the effect of automatically proportioning the angular movement of the lever 55 to compensate for the increased effective leverage resulting from the movement of the link 56 outwardly 80 of this lever, with the upward sliding movement of the carriage 30, and when, with the continued descent of the plunger this increased effective leverage is not sufficient to impart the desired quantity of movement to 85 the carriage 30, by reason of the progressively decreasing leverage between the lever 55 and the bearing member 60, to increase the angular speed of the lever 55. Consequently, notwithstanding constant variation of the effective leverage of the lever 55 and link 56, and between the lever 55 and the bearing member 60, the quantity of the movement of the carriage 30, toward the tapes 11, will be substantially 90 the same during every part of the vertical movement of the plunger.

While I have above referred to the operative effect of the mechanisms described when lowering the shelf, it is obvious that the same effects will be secured, but in reverse order, 100 when raising the shelf. This raising of the shelf, however, with the collecting shelf or table set at an angle to the horizontal, is seldom necessary unless by oversight an operator should lower the table beyond the point required.

It is to be noted that the arrangement of the bearing straps 32, 33, 34 and 35 is such that the movements of the carriage 30, toward or from the tapes 11, will cause the shelf 110 or table 31 to have movement therewith. These straps are merely used to permit the adjustment of the table or shelf 31 laterally of the carriage 30 by means of the gears 43-44, the racks 45 and 46, said gears being 115 actuated by means of the shaft 40, enmeshed gears 39 and 41, shaft 37 and hand wheel 38. This adjustment is merely for the purpose of accurately positioning the side gauge board 49 so as to secure a neat stacking of the sheets. This side board 49 and the tail board 48 are positioned upon the table or shelf 31 preparatory to a run of the machine so as to properly receive sheets of a certain size. 120 If a succeeding run is upon sheets of a different size, these boards may be readjusted. The lateral adjustment of the table or shelf 31 upon the carriage 30, is merely to permit a more accurate adjustment of the side gauge 130

board 49 than is possible by fixed openings as described.

Ordinarily the collecting table or shelf will be set at the angle shown in Figs. 1 and 2. This, however, is not necessary since the base frame supported from the plate 14 may be adjusted about the bearing pin 16 by means of the segmental worm wheel 18 and the worm shaft 20 co-operating therewith, this shaft being mounted in said base plate. 10 The shelf may be tilted at any desired angle to the horizontal by turning this shaft, the stop 21 limiting, however, the movement of the frame in one direction to a horizontal position, and the link and lever mechanism 55 and 56 through the bracket 59 limiting the turning movement of the frame in the other direction.

It will be noted that the sliding connection 20 between the lever 55 and the link 56 will permit the turning of the collecting table or shelf with the base frame, and that during such turning movement, the floating carriage 30 and the table or shelf 31 will have no 25 movement toward or from the tapes 11, irrespective of the direction of rotary movement of the collecting shelf or table. If the edge of the table or shelf adjacent the delivery tapes be moved downwardly, the bracket 59, 30 being offset from the bearing pin 16, will tend to move in an upward arc. The lever 55 and the bearing member 60 will resist this arcuate movement, however, and cause the base frame to have movement in relation to the 35 carriage 30. If moved in the opposite direction, the link 56 will permit a downward movement of the bracket 59, but the lever 55 and the bearing member 60 will prevent any 40 rotative movement of said bracket so that the base frame will have movement in relation to said carriage in the opposite direction.

Hence these adjustments can have only the effect of changing the angularity of the table or shelf 31 to the horizontal, and the angularity of the back or tail board 48 to the vertical.

Upon the completion of a run of the machine, the plunger 13 may be at, or brought to, its lowermost position when it is desired 50 to remove the collected sheets from the table or shelf 31, the worm segment and shaft 18 and 20 then being actuated to bring the base frame, and the parts carried thereby, to a horizontal position. The side gauge board 55 49 is then removed from the table or shelf 31 and the wetting board, with the collected sheets thereon, slid from the table or shelf upon a suitable hand truck.

The bearing pin 16 upon the plunger 13, 60 the co-operating lugs 15 upon the plate 14 of the base frame, and the brackets 54 and 59 connected with the link and lever mechanism 55 and 56, afford diverging supports for the collecting table or shelf, their offset 65 relation permitting the adjustment of the an-

gularity of the table and of the back or tail board in the manner above described.

By using a plunger and hydraulic power, as described, the controls for this power may not only be brought closely adjacent the chair of the operator, so as to permit the convenient 70 raising or lowering of the table or shelf, but the water in the cylinder 12 will maintain the table at the desired elevation, irrespective of the load thereon. This condition also permits a positive but slow movement of the 75 table so that the adjustment may be accomplished without interrupting the actuation of the unwinding or other machine.

In fact, during the operation of the machine, the operator may make any of the herein described adjustments while still inspecting the work. The various adjustments may be made of the height of the collecting table or shelf and its angularity without interrupting the operation of the unwinding machine, which is also true as to a lateral adjustment 85 of the collecting shelf proper 31.

The back or tail board 48 will, with the descent of the plunger, move in a substantial- 90 ly straight line, or remain in the plane in which it is originally positioned by the angular setting of the collecting table or shelf 31. Consequently, as stated, with the re-setting of said table or shelf, notwithstanding 95 its change of position in relation to the tapes 11 and because of this change of position, the operative portion of the tail board, so far as receiving sheets is concerned, will always be the same, and this condition will prevail during every portion of the downward movement of the table or shelf. The inclination of the table or shelf 31 may be changed at will without any substantial variation in the distance between the delivery point of the 100 tapes 11 and the back or tail board, since this distance is determined by the lever and link mechanism 55 and 56.

It is not my intention to limit this invention to the precise details of construction 110 shown in the accompanying drawings, it being apparent that such may be varied without departing from the spirit and scope of the invention.

Having described the invention, what I 115 claim as new and desire to have protected by Letters Patent, is:—

1. A sheet delivery machine including therein a collecting mechanism embodying a cylinder, a plunger mounted therein, means controlling the application of power to said plunger, a frame carried by said plunger, a collecting shelf slidably mounted upon said frame, a lever pivotally connected and movable with said plunger and set obliquely of the axis thereof, a bearing member engageable with said lever, and operative connections between said lever and said shelf, whereby the oscillations of said lever with the vertical 120

movements of said plunger will impart movement to said shelf along said frame.

2. A sheet delivery machine including therein a collecting mechanism embodying a cylinder, a plunger mounted therein, means controlling the application of power to said plunger, a frame carried by said plunger, a collecting shelf slidably mounted upon said frame, a lever pivotally connected and movable with said plunger and set obliquely of the axis thereof, a bearing member engageable with said lever, a link slidably mounted upon said lever, and a pivotal connection between said link and said shelf, whereby the oscillations of said lever with the vertical movements of said plunger will impart movement to said shelf along said frame.

3. A sheet delivery machine including therein a collecting mechanism embodying a cylinder, a plunger mounted therein, means controlling the application of power to said plunger, a frame carried by said plunger, a collecting shelf slidably mounted upon said frame, means whereby said frame and said shelf may be set at an angle to, or brought to a horizontal plane, a lever pivotally connected and movable with said plunger and set obliquely of the axis thereof, a bearing member engageable with said lever, and operative connections between said lever and said shelf, whereby the oscillations of said lever with the vertical movements of said plunger will impart movement to said shelf along said frame.

35. 4. A sheet delivery machine including therein a collecting mechanism embodying a cylinder, a plunger mounted therein, means controlling the application of power to said plunger, a frame carried by said plunger, a collecting shelf slidably mounted upon said frame, means whereby said frame and said shelf may be set at an angle to, or brought to a horizontal plane, a lever pivotally connected and movable with said plunger and set obliquely of the axis thereof, a bearing member engageable with said lever, a link slidably mounted upon said lever, a pivotal connection between said link and said shelf, whereby the oscillations of said lever with the vertical movements of said plunger will impart movement to said shelf along said frame, and an arcuate cam surface on said lever, whereby said shelf will receive uniform right line movement irrespective of variance in the effective leverage of said lever and link, and in the effective leverage of said bearing member upon said lever.

5. A sheet delivery machine including therein a collecting mechanism embodying a cylinder, a plunger mounted therein, means controlling the application of power to said plunger, a frame carried by said plunger, a collecting shelf consisting of a floating carriage, mounted upon said frame to have sliding movement in one direction, a shelf prop-

er mounted upon said carriage to have sliding movement at right angles to the movement of said carriage, means whereby said shelf may be adjusted in relation to said carriage, a lever pivotally connected and movable with said plunger and set obliquely of the axis thereof, a bearing member engageable with said lever, and operative connections between said lever and said carriage, whereby the oscillations of said lever with the vertical movements of said plunger will impart movement to said carriage and said shelf along said frame.

6. A sheet delivery machine including therein a collecting mechanism embodying a cylinder, a plunger mounted therein, means controlling the application of power to said plunger, a frame carried by said plunger, a collecting shelf consisting of a floating carriage, mounted upon said frame to have sliding movement in one direction, a shelf proper mounted upon said carriage to have sliding movement at right angles to the movement of said carriage, means whereby said shelf may be adjusted in relation to said carriage, a lever pivotally connected and movable with said plunger and set obliquely of the axis thereof, a bearing member engageable with said lever, a link slidably mounted upon said lever, and a pivotal connection between said link and said carriage, whereby the oscillations of said lever with the vertical movements of said plunger will impart movement to said carriage and said shelf along said frame.

7. A sheet delivery machine including therein a collecting mechanism embodying a cylinder, a plunger mounted therein, means controlling the application of power to said plunger, a frame carried by said plunger, a collecting shelf consisting of a floating carriage, mounted upon said frame to have sliding movement in one direction, a shelf proper mounted upon said carriage to have sliding movement at right angles to the movement of said carriage, means whereby said shelf may be adjusted in relation to said carriage, means whereby said frame may be set at an angle to, or brought to a horizontal plane, a lever pivotally connected and movable with said plunger and set obliquely of the axis thereof, a bearing member engageable with said lever, and operative connections between said lever and said carriage, whereby the oscillations of said lever with the vertical movements of said plunger will impart movement to said carriage and said shelf along said frame.

8. A sheet delivery machine including therein a collecting mechanism embodying a cylinder, a plunger mounted therein, means controlling the application of power to said plunger, a frame carried by said plunger, a collecting shelf consisting of a floating carriage, mounted upon said frame to have sliding movement in one direction, a shelf proper

mounted upon said carriage to have sliding movement at right angles to the movement of said carriage, means whereby said shelf may be adjusted in relation to said carriage, a lever pivotally connected and movable with said plunger and set obliquely of the axis thereof, a bearing member engageable with said lever, a link slidably mounted upon said lever, a pivotal connection between said link and said carriage, whereby the oscillations of said lever with the vertical movements of said plunger will impart movement to said carriage and said shelf along said frame, and an arcuate cam surface on said lever, whereby said carriage will receive uniform right line movement irrespective of variance in the effective leverage of said lever and said link, and in the effective leverage of said bearing member and said lever.

20 9. A sheet delivery machine including therein a collecting mechanism embodying a cylinder, a plunger mounted therein, means controlling the application of power to said plunger, a bearing pin fixedly supported upon said plunger, a frame rotatably mounted upon said bearing pin, a segmental worm gear carried by said pin, a worm shaft co-operating therewith, whereby said frame may be set at an angle to, or brought to a horizontal plane, a collecting shelf slidably mounted upon said frame, a lever pivotally connected and movable with said plunger and set obliquely of the axis thereof, a bearing member engageable with said lever, a link 25 slidably mounted upon said lever, a pivotal connection between said link and said shelf, whereby the oscillations of said lever with the vertical movements of said plunger will impart movement to said shelf along said frame, and an arcuate cam surface on said lever, whereby said shelf will receive uniform right line movement irrespective of variance in the effective leverage of said lever and link, and in the effective leverage of said bearing member upon 30 said lever.

40 10. A sheet delivery machine including therein a collecting mechanism embodying a cylinder, a plunger mounted therein, means controlling the application of power to said plunger, a frame carried by said plunger, a collecting shelf slidably mounted upon said frame, a back or tail board adjustably mounted upon said shelf, a side gauge board adjustably mounted upon said shelf, means 45 whereby said frame and said shelf may be set at an angle to, or brought to a horizontal plane, a lever pivotally connected and movable with said plunger and set obliquely of the axis thereof, a bearing member engageable with said lever, a link slidably mounted upon said lever, a pivotal connection between said link and said shelf, whereby the oscillations of said lever with the vertical movements of said plunger will impart movement 50 to said shelf along said frame, and an arcuate

cam surface on said lever, whereby said shelf will receive uniform right line movement irrespective of variance in the effective leverage of said lever and link, and in the effective leverage of said bearing member upon said lever. 70

11. A sheet delivery machine including therein a collecting mechanism embodying a cylinder, a plunger mounted therein, means controlling the application of power to said plunger, a frame carried by said plunger, a collecting shelf slidably mounted upon said frame and having a longitudinally extending slot in the upper surface thereof, and a plurality of sets of spaced openings at one side 75 of said slot, a back or tail board adjustably mounted upon said shelf by means of said slot, a side gauge board adjustably mounted upon said shelf in said openings, means whereby said frame and said shelf may be set at an angle to, or brought to a horizontal plane, a lever pivotally connected and movable with said plunger and set obliquely of the axis thereof, a bearing member engageable with said lever, a link slidably mounted 80 upon said lever, a pivotal connection between said link and said shelf, whereby the oscillations of said lever with the vertical movements of said plunger will impart movement to said shelf along said frame, and an arcuate cam surface on said lever, whereby said shelf will receive uniform right line movement irrespective of variance in the effective leverage of said lever and link, and in the effective leverage of said bearing member upon 85 said lever. 90

12. A sheet delivery machine including therein a collecting mechanism embodying a vertical cylinder, a plunger mounted therein, means controlling the application of power to said plunger, a frame inclined to the horizontal and carried by said plunger, a collecting shelf slidably mounted upon said frame, a slide mounted upon said cylinder, connections between same and said plunger, said slide being substantially parallel with the axis of said cylinder, an offset bracket carried by said slide extending on one side of the axis of said cylinder, a bracket carried by said shelf upon the other side of the axis of said cylinder, a lever pivotally connected with said bracket, a link slidably mounted upon said lever and pivotally connected with the bracket upon said shelf, whereby said lever and said link extend obliquely to the axis of said cylinder, and a fixed bearing member adjacent the top of said cylinder and engageable with said lever, whereby vertical movement of said plunger will impart an oscillatory movement to said lever and said link, and cause movement of said shelf along 100 said frame. 110

13. A sheet delivery machine including therein a collecting mechanism embodying a cylinder, a plunger mounted therein, means 105

controlling the application of power to said plunger, a collecting shelf carried by and slidably mounted in relation to said plunger, co-operating means movable with said plunger and connected with said shelf, and means acting upon said cooperating means whereby sliding movement will be imparted to said shelf simultaneously with its movement with said plunger.

10 14. A sheet delivery machine including therein a collecting mechanism embodying an hydraulic cylinder, a plunger mounted therein, valve controlled pipe lines leading to and from said cylinder, a collecting shelf carried by and slidably mounted in relation to said plunger, means whereby said shelf may be set at an angle to, or brought to a horizontal plane, a lever pivotally connected and movable with said plunger and set 15 obliquely of the axis thereof, a bearing member engageable with said lever, a link slidably mounted upon said lever, a pivotal connection between said link and said shelf, whereby the oscillations of said lever with 20 the vertical movement of said plunger will impart movement to said shelf along said frame, and an arcuate cam surface on said lever, whereby said shelf will receive uniform right line movement irrespective of 25 variance in the effective leverage of said lever and link, and in the effective leverage of said bearing member upon said lever.

In witness whereof I have hereunto affixed my signature, this 25th day of March, 1929.

JAMES P. ERIKSEN.
